JOSEPH O. CADIEUX, OF MERIDEN, CONNECTICUT, ASSIGNOR TO CONNECTICUT TELEPHONE & ELECTRIC CORPORATION, OF MERIDEN, CONNECTICUT, A CORPORATION OF DELAWARE

ANNUNCIATOR PANEL

Application filed March 6, 1930. Serial No. 433,671.

This invention relates to the manufacture of indicia panels and more particularly to that type associated with electric annunciators and the like.

5 A principal object of my invention provides an indicia panel which presents a uniform surface capable of sharply defining the indicia thereon when illuminated.

Another object of my invention provides 10 a panel that may be easily cleaned without the resultant chipping of the indicia due to constant rubbing and washing of the surface, thereby effecting a high degree of sanitation and an economy in replacement.

15 A further object provides a panel that is simple in construction, inexpensive to manufacture and highly efficient in use.

Other objects and advantages will be apparent from the following description, appended claim and annexed drawing.

In its preferred embodiment the panel consists of a transparent body provided with an opaque coating in which suitable indicia is cut and a translucent coating applied over-all. This is made by first applying a number of coatings of enamel or paint to the surface of the transparent body sufficient to make it opaque. The indicia is then cut therein and the portion forming the same removed. Another coating of translucent material is then applied overall, thus forming a panel that presents an apparent uniform opaque surface until a bright light shines behind it—whereupon the symbol, letter or number shows distinctly.

Referring to the drawing wherein—

Fig. 1 is a perspective view partly in section of a conventional type of annunciator box, my invention being applied thereto.

40 Figs. 2, 3, 4, 5 and 6 are fragmentary sectional views showing various steps in making a panel according to my invention.

As illustrated in the drawing, a conventional type of annunciator box 20 is provided 45 with opaque walls 21. A suitable signal or pilot light 22 is placed therein and serves to illuminate an indicia panel 25, forming one of the side walls, which if desired may be hinged to the box in any convenient manner to form 50 a door or the like.

As heretofore set forth, it is highly desirable to have an indicia panel that will present a substantially uniform surface as well as to sharply define the various characters formed thereon when illuminated. To accomplish this I provide a panel composed of a sheet of glass 26 or any other suitable transparent material, upon the surface of which I apply one or more coatings of enamel 27 or any translucent material adaptable for this purpose as indicated in Fig. 2 of the drawing. Over this coating 27 I apply a second coating 28 (Fig. 3) consisting of any material which will render the surface opaque, preferably that of a metallic paint such as aluminum bronze, which is followed by the application of another coating 29 (Fig. 4) of enamel or the like and which may be of the character used in the first application. The panel will now present a smooth 60 uniform surface of opaqueness.

It is desirable at this time to form thereon the indicia 30, which may be that of letters, numerals or symbols. This, I accomplish by removing portions of the various coatings 27, 28 and 29 as indicated at 31 in a manner to form the required indicia upon the surface of the glass 26, the removed portions being indicative of the character, numeral or symbol desired while the background is formed of the various coatings, this being clearly illustrated in Fig. 5 of the drawing.

However, it will be understood, that the removed portions may form the background, the indicia being formed of the various coatings.

In order that the panel will present an apparently entire opaque surface when not illuminated, I next cover the entire surface including that from which the various coatings have been removed with a final application of material 32 such as the enamel used in the previous coatings 27 and 29, although any other suitable translucent material may be used as shown in Figs. 1 and 6. It will be apparent, that the final coating 32 will serve to protect the edges of the indicia from chipping and that the panel will at all times present a substantially uniform appearance, and

the openings formed in the undercoatings will be covered in a manner to simulate opaqueness adapted to conform to the tone of the balance of the panel.

When illuminated from the rear, the indicia, formed by removing portions of the under-coatings, will be sharply defined through that of the outer or final coating.

The paint or enamel should be of a character such that it adheres tightly to the foundation. Preferably the paint or enamel such as "Duco" is applied by spraying under pressure.

By putting a coat of such enamel over the bronze or similar opaque paint it is easier to obtain clear cut edges when forming the stencil or symbol outline.

This method of manufacture produces a sharp clear cut signal when the light is turned on even when the electric light bulb is placed close to the glass as is most desirable in shallow box annunciator constructions.

It is to be distinctly understood that while I have illustrated and described a preferred embodiment of my invention, various changes and modifications may be made without departing from the spirit and scope of the appended claim.

I claim:

An annunciator panel comprising a transparent supporting body, an opaque coating superimposed on the outside of said body and provided with openings to form indicia, the edges of the coating around the openings being thin and sharp, an outer translucent coating applied to and extending over said opaque coating, said edges and the exposed portion of said transparent body, said outer coating being formed with a continuous and uniform light reflecting surface, and a light source behind the supporting body at the side opposite to the coatings.

JOSEPH O. CADIEUX.
